[57] CLAIM

The ornamental design for an electronic wallet, as shown and described.

DESCRIPTION

FIG. 1 is a front, top and right side perspective view of an electronic wallet showing our new design;
FIG. 2 is a top plan view thereof;
FIG. 3 is a front elevational view thereof;
FIG. 4 is a left side elevational view thereof;
FIG. 5 is a right side elevational view thereof;
FIG. 6 is a rear elevational view thereof;
FIG. 7 is a bottom plan view thereof; and,
FIG. 8 is a front, top and right side perspective view thereof showing the state in which a card, shown in broken lines, is about to be inserted into the electronic wallet, for illustrative purpose only, and which card forms no part of the claimed design.
